DESIGN FOR A TEXTILE FABRIC OR SIMILAR ARTICLE

Irene Weitz, Brooklyn, N. Y.

Application November 19, 1936, Serial No. 66,019

Term of patent 3½ years

To all whom it may concern:

Be it known that I, Irene Weitz, a citizen of the United States, residing in Brooklyn, New York, whose post-office address is 1450 Broadway, Borough of Manhattan, city of New York, county of New York, and State of New York, have invented a new, original, and ornamental Design for a Textile Fabric or Similar Article, of which the following is a specification, reference being had to the accompanying drawing, forming a part thereof.

The figure is a plan view of the fabric embodying my design.

I claim:

The ornamental design for a textile fabric or similar article as shown.

IRENE WEITZ,
